UNITED STATES PATENT OFFICE.

WILLIAM E. BEE, OF DETROIT, MICHIGAN, ASSIGNOR TO PALMER-BEE COMPANY, OF DETROIT, MICHIGAN, A CORPORATION OF MICHIGAN.

REDUCTION GEARING.

Application filed March 5, 1923. Serial No. 622,958.

The invention relates to reduction gearing and has among its objects the provision of a reduction gearing embodying a worm drive; a reduction gearing having provision for transmitting power at opposite sides thereof; a reduction gearing having a housing provided with a cover through which the drive shaft extends and which is removable without disturbing the mechanism within the housing; and a reduction gearing in which the power shaft supports the drive shaft. Other objects of the invention reside in the novel features of construction and combinations and arrangements of parts as more fully hereinafter set forth.

In the drawings:

Figure 1 is an end elevation of a reduction gearing embodying my invention;

Figure 2 is a plan view thereof with the housing cover removed;

Figure 3 is a cross section on the line 3—3 of Figure 2;

Figure 4 is a cross section on the line 4—4 of Figure 3.

1 and 2 are respectively the lower section and upper section or cover of the housing of the reduction gearing; and 3 and 4 are respectively the power shaft and the counter shaft extending transversely of the housing 30 and parallel to each other, the axes of these shafts being in the meeting edges of the lower section and cover of the housing and the power shaft extending laterally beyond the opposite sides of the housing so that either or both sides of this power shaft may be used in transmitting power. These two shafts are journalled in the bearing members 5 and 6 supported upon the lower section 1 of the housing and therewithin at its opposite sides, these bearing members having detachable caps.

The gearing mechanism comprises the worm 7, the worm wheel 8 meshing with the worm and secured to the sleeve 9 by suitable means such as the key 10. This sleeve is rotatably mounted upon the power shaft 3 adjacent to the bearing member 5 and has secured to its inner end the pinion 11 which as shown, is integral therewith.

This pinion meshes with the gear 12 secured 50 upon the counter shaft 4 to which is also secured the pinion 13 meshing with the gear 14 secured upon the power shaft 3, the securing means for the gears 12 and 14 and the pinion 13 preferably comprising keys. 55

The shaft 15 upon which the worm 7 is formed extends through the rear end of the cover 2 of the housing and has its outer end detachably secured to the flexible coupling 16 which in turn is secured to the shaft 17 60 of the motor 18, this motor being mounted upon the bracket 19 detachably secured to the rear end of the lower section 1 of the reduction gearing housing.

The worm shaft is mounted upon the 65 power shaft and its support 20 comprises the spaced side frames 21 on opposite sides of the worm wheel 8 and having hubs 22 journalled upon the pinion sleeve 9. The rear lower ends of these side frames have 70 lateral lugs 23 formed thereon which rest upon and are secured to lateral lugs 24 formed upon the rear end of the lower section 1 of the housing, the securing means comprising bolts 25 extending through these 75 lugs. By securing the rear end of the support to the rear wall of the lower section the support is held from rotation about the pinion sleeve. The support has at the upper edges of the side frames 21 and at the 80 opposite ends thereof the annular enlargements 26 and 27 carrying the anti-friction bearings 28 and 29 respectively which support the worm shaft 15 near its opposite ends. The opening through the rear annular enlargement 27 is of sufficient diameter to permit of the passage longitudinally therethrough of the worm 7.

30 is a detachable closure in the rear end of the housing cover 2 surrounding the worm shaft 15 and having spaced inner and outer walls 31 and 32 respectively forming a chamber for receiving any lubricant thrown off the annular bevelled shoulder 33 of the worm shaft. This chamber communicates 90 with the interior of the housing through suitable passages 34 in the lower part of the inner wall 31. The opening in the end wall

of the cover 2 which is closed by the closure 30 is of sufficient diameter to permit upon the removal of the flexible coupling 16 and of the closure 30, of tilting the forward end 5 of the cover 2 upwardly and at the same time moving the same rearwardly until the rear end of the cover has passed over the outer end of the worm shaft 15 at which time the cover is free to be raised from the lower 10 section of the housing.

From the above description it will be readily seen that I have provided a reduction gearing having a housing provided with a cover through which the drive shaft 15 extends, this cover being removable without disturbing the mechanism within the housing. Furthermore, that I have provided a simple construction for supporting the worm upon the power shaft. Furthermore, that 20 the power shaft is adapted to transmit power at either or both ends of the reduction gearing, this being very desirable in certain instances as for example when the reduction gearing is used in conjunction with a pair 25 of parallel conveyors.

What I claim as my invention is:

1. In a reduction gearing, the combination with a power shaft and a counter shaft, of a sleeve rotatably mounted upon said power 30 shaft, a pinion secured to said sleeve, a gear meshing with said pinion and secured to said counter shaft, a pinion secured to said counter shaft, a gear secured to said power shaft, a worm wheel secured to said sleeve, 35 and a worm meshing with said worm wheel for driving the same.

2. In a reduction gearing, the combination with a housing and a power shaft, of reducing gearing for driving said shaft including a member mounted thereon, a drive member cooperating with said first-mentioned member and extending transversely thereof and carried upon said shaft, and means for securing said drive member in 45 fixed relation to said housing.

3. In a reduction gearing, the combination with a housing and a power shaft, of gearing for driving said power shaft including a worm wheel mounted thereon, and a 50 worm meshing with said worm wheel and carried by said power shaft, and means for securing said worm in fixed relation to said housing.

4. In a reduction gearing, the combination 55 with a housing and a shaft, of gearing for driving said shaft including a worm wheel mounted thereon, a drive shaft having a worm cooperating with said worm wheel and a support mounted upon said first-mentioned 60 shaft and having bearing portions in which said worm shaft is journalled, said support being connected to said housing.

5. In a reduction gearing, the combination 65 with a power shaft and a counter shaft, of gearing mounted upon said shafts for driv-

ing said power shaft, said gearing including a worm wheel revolubly carried by said power shaft, a drive shaft having a worm meshing with said worm wheel, and a support for said worm shaft comprising side frames at opposite sides of said worm wheel and provided with bearing portions beyond the periphery of said worm wheel in which 70 said worm shaft is journalled.

6. In a reduction gearing, the combination 75 with a housing section, of a power shaft and counter shaft carried thereby, gearing upon said power shaft and counter shaft for driving said power shaft, said gearing including a worm wheel rotatably carried by said power shaft, a drive shaft having a worm meshing with said worm wheel, and a support rotatably mounted upon said power shaft and provided with bearing portions in 80 which said worm is journalled and with 85 means for attachment to said housing section.

7. In a reduction gearing, the combination 90 with the lower section of a housing, of a power shaft journalled thereon and extending therethrough, gearing for driving said power shaft including a worm wheel mounted thereon, a drive shaft extending transversely of 95 said power shaft and having a worm meshing with said worm wheel, a cover detachably secured to said lower section and having an opening therein through which said drive shaft extends, said opening being of a size to permit of the complete removal of said cover by combined tilting and lateral movement and subsequent upward movement, and a closure for the opening in said cover detachably secured to said cover.

8. In a reduction gearing, the combination 100 of a housing section, of a cover detachably secured thereto, a power shaft journalled upon said housing section, a drive shaft extending through said cover and carried upon 105 said power shaft and gearing between said drive shaft and power shaft for driving the latter from the former, said cover having 110 provision for its removal without disturbing the gearing.

9. In a reduction gearing, the combination 115 with the lower section of a housing, of a power shaft journalled thereon and extending therethrough, gearing for driving said power shaft including a worm wheel mounted 120 thereon, a drive shaft extending transversely of and mounted upon said power shaft and having a worm meshing with said worm wheel, a cover detachably secured to 125 said lower section and having an opening therein through which said drive shaft extends, said opening being of a size to permit of the complete removal of said cover by combined tilting and lateral movement and subsequent upward movement, and a closure for the opening in said cover detachably secured to said cover.

10. In a reduction gearing, the combina- 130

tion with a housing and a shaft having a portion therewithin, of mechanism for driving said shaft including a sleeve rotatably mounted thereon, spaced gear members non-
rotatably secured upon said sleeve, and a third gear member meshing with one of said first mentioned gear members, and side

frames at opposite sides of and positioning the gear member in mesh with said third gear member, said side frames being connected to said housing. 10

In testimony whereof I affix my signature.

WILLIAM E. BEE.
